UNITED STATES PATENT OFFICE.

JENNIE SHEILS, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 17,976, dated December 20, 1887.

Application filed November 10, 1887. Serial No. 254,875. Term of patent 3½ years.

To all whom it may concern:

Be it known that I, JENNIE SHEILS, of the city, county, and State of New York, have invented and produced a new and original Design for a Pattern of a Lady's Costume; and I do hereby declare that the engraved prints accompanying this specification convey to any one accustomed to using paper patterns a clear understanding of how a garment made up by the pattern will appear.

The design shows a basque and a round walking-skirt. The skirt displays a plain panel on the left side gore; a full front drapery that exhibits rows of shirrings at the top, falls to the edge of the skirt at the right side, and is lifted high at the left side by a group of plaits some distance below the shirrings, and a full back drapery that falls even with the

edge of the skirt and exhibits plaits high up in the side edges, and loopings. The basque displays its fronts opening in fancy curves over a close-fitting vest that exhibits plaited surplice ornaments flaring slightly above the bust, the fronts meeting at the lower edge of the vest; a close-fitting back that exhibits fan plaits underfolded below the waist-line of its center seam; coat-sleeves, and a standing collar.

What I claim as my invention, and desire to secure by Letters Patent, is—

The design for a lady's costume, as shown in the engraved prints accompanying this specification.

JENNIE SHEILS.
